[57] CLAIM

The ornamental design for a bottle with pump and handle, as shown and described.

DESCRIPTION

FIG. 1 is a perspective view of a bottle with pump and handle, embodying our new design;

FIG. 2 is a back elevational view thereof;

FIG. 3 is a front elevational view thereof;

FIG. 4 is a side elevational view thereof and the other side elevational view thereof being the same; and,

FIG. 5 is a top view thereof.

The broken line showing of the lower portion of a bottle is for illustrative purposes only and forms no part of the claimed design.
